Primary Examiner—Prabhakar Deshmukh(74) *Attorney, Agent, or Firm*—Marshall & Melhorn, LLC(57) **CLAIM**

The ornamental design for a package for computer cable, as shown and described.

DESCRIPTION

FIG. 1 is a fragmentary top plan view of a package for computer cable showing my new design;
 FIG. 2 is a fragmentary right side elevational view thereof;
 FIG. 3 is a fragmentary front elevational view thereof;
 FIG. 4 is a fragmentary rear elevational view thereof;
 FIG. 5 is a sectional view taken along line 5—5 of FIG. 1; and,
 FIG. 6 is a sectional view taken along line 6—6 of FIG. 1. The broken lines are for illustrative purpose only and form no part of the claimed design.
